DESIGN FOR A SHOE SHINE BOX

Joseph T. Pearson, Jr., Huntingdon Valley, Pa.

Application January 17, 1946, Serial No. 125,657

Term of patent 7 years

(Cl. D58—4)

To all whom it may concern:

Be it known that I, Joseph T. Pearson, Jr., a citizen of the United States, residing at Huntingdon Valley, in the county of Montgomery and State of Pennsylvania, have invented a new, original, and ornamental Design for a Shoe Shine Box, of which the following is a specification, reference being had to the accompanying drawing, forming a part thereof.

I claim:

The ornamental design for a shoe shine box, as shown.

JOS. T. PEARSON, JR.
